(57) **CLAIM**

I claim, the ornamental design for a heater case for a heating cooker, as shown and described.

DESCRIPTION

FIG. 1 is a top and front perspective view of a heater case for a heating cooker, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
